[57] CLAIM

The ornamental design for a mobile home, as shown and described.

DESCRIPTION

FIG. 1 is a front elevation view of a mobile home showing my new design.

FIG. 2 is a perspective view thereof on a reduced scale.

FIG. 3 is a rear elevation view thereof.

The side of the mobile home not shown is a mirror image of the side shown in FIG. 2.

The broken lines in the drawing are for illustrative purposes only.

FIG. 1FIG. 2
